(57) **CLAIM**

The ornamental design for a mailing machine, as shown and described.

DESCRIPTION

FIG. 1 is a top, front and left side perspective view of a mailing machine according to the invention;

FIG. 2 is a front view thereof;

FIG. 3 is a top plan view thereof;

FIG. 4 is a right side view thereof;

FIG. 5 is a left side view thereof; and,

FIG. 6 is a rear view thereof.

The structural features depicted by means of broken lines in FIGS. 1-5 have been shown for illustrative purposes only and form no part of the claimed design.
